UNITED STATES PATENT OFFICE.

GEORGE A. STRAWSER, OF PFOUTS VALLEY, PENNSYLVANIA, ASSIGNOR OF ONE-HALF
TO A. L. LONG, OF MILLERSTOWN, PENNSYLVANIA.

SPIKE.

1,025,596.

Specification of Letters Patent.

Patented May 7, 1912.

Application filed October 9, 1911. Serial No. 653,529.

To all whom it may concern:

Be it known that I, GEORGE A. STRAWSER, a citizen of the United States, residing at Pfouts Valley, in the county of Perry, State 5 of Pennsylvania, have invented certain new and useful Improvements in Spikes; and I do hereby declare the following to be a full, clear, and exact description of the invention, such as will enable others skilled in the art 10 to which it appertains to make and use the same.

This invention relates to spikes and has for an object to provide a spike and key therefor serving to lock the spike against 15 accidental withdrawal.

In many of the key equipped spikes, the key when driven home must form its own groove in the tie, and consequently, due to the frailty of the key, the latter is often 20 times bent and distorted during driving home and thus the utility of the key impaired or its complete withdrawal and replacement with a new key necessitated. To obviate this disadvantage, I provide a 25 groove forming projection on the key receiving face of the spike, this projection being so formed as to not impede driving of the spike to final position while at the same time being so formed as to make a 30 groove in the tie of sufficient size to receive the key.

A further object of this invention is to provide the groove making projection with a cam face which will bend outwardly the 35 penetrating end of the key so that the penetrating end together with the adjacent portions of the spike coact in forming a lock which will positively prevent accidental withdrawal of the spike.

With the above objects in view the invention consists of the certain novel details of construction and combination of parts hereinafter fully described and claimed, it being understood that various modifications may 45 be made in the minor details of construction within the scope of the appended claim.

In the accompanying drawing forming part of this specification:—Figure 1 is a side elevation of my improved spike with 50 the key shown in full lines in initial position for driving, and in dotted lines in final position. Fig. 2 is a rear elevation of the spike with the parts as shown in full lines

in Fig. 1. Fig. 3 is a cross section on the line 3—3 Fig. 1. Fig. 4 is a cross section on 55 the line 4—4 Fig. 1.

Referring now to the drawing in which like characters of reference designate similar parts, 10 designates a spike which terminates at one end in a head 11, and at its 60 opposite end in a chisel point 12. Formed in one face of the spike is a longitudinal rabbet 13, this rabbet beginning at the head of the spike and terminating below the center of the spike, and gradually increasing 65 in depth from both ends to the center. The value of this form of rabbet is that it causes the shank of the hereinafter described key to be bent or bowed throughout its entire length during driving to final position. 70

The spike is equipped at the lower end of the rabbet 13 with a projection 14 having an inclined face 15 which forms a continuation of one of the faces of the chisel point, and an inclined face 16 which slopes in an 75 opposite direction from the face 15 and forms a continuation of the bottom wall of the rabbet. The face 16 acts as a cam which co-operates with the concave bottom wall of the rabbet in bending the above mentioned 80 key as will be presently described. The projection is substantially the same in width at its juncture with the rabbet as the rabbet itself, and the sides 17 are cut away from points adjacent to said juncture to the extreme lower end of the projection meeting in a penetrating point 17'. The projection, intermediate the inclined faces 15 and 16, is approximately square in cross section and of less width than the rabbet. Upon driving 90 of the spike to final position, this projection will form a groove in the tie which registers with the rabbet in the spike and coacts therewith in forming a key way.

The key comprises a shank 18 which is 95 approximately square in cross section and terminates at one end in a head 19 and at its opposite end in a beveled face 20 which forms a penetrating point. The key is of such diameter as to somewhat snugly fit 100 within the key way as shown in Figs. 1 and 2.

In inserting the key, the beveled leading face 20 is turned away from the bottom wall of the rabbet. During driving of the 105 key to final position, by virtue of the pene-

trating point of the spike bearing upon the bottom wall of the rabbet, the spike will be bent or bowed, this bending being more pronounced as the spike rides out on the cam face of the projection 14 and thus the key is bowed throughout its entire length. By virtue of the curvature being more abrupt at the leading end of the key, a wedge or lock is formed by the free end of the key 10 and adjacent portions of the spike which will positively prevent accidental withdrawal of the spike.

It will be noted, and this feature is deemed of importance, that the key way 15 formed by the groove made in the tie and the rabbet, permit of the key being easily driven to final position, and thus distortion of the key during driving positively prevented.

What is claimed, is:—

The combination of a spike having a longitudinal rabbet in one side spaced from the edges of the side and formed with a curvilinear bottom wall which merges gradually at the ends into said side, a groove making 25 projection on said spike having a cam face forming a continuation of said wall, and a key in said rabbet adapted to be bowed through substantially its entire length by said wall and face during driving to final 30 position.

In testimony whereof, I affix my signature, in presence of two witnesses.

GEORGE A. STRAWSER.
